Des. 208,937
Patented Oct. 17, 1967

208,937

LIGHTING FIXTURE

Roger F. De Merritt, St. Clairsville, Ohio, assignor to Sylvania Electric Products Inc., a corporation of Delaware

Filed June 16, 1966, Ser. No. 2,699

Term of patent 14 years

(Cl. D48—4)

The broken line disclosure of a lamp bulb is for illustrative purposes only.

I claim:

The ornamental design for a lighting fixture, as shown and described.
